UNITED STATES PATENT OFFICE.

GIDEON P. KIDD, OF ROANN, INDIANA.

AUTOMATIC GRAVITY-GATE.

SPECIFICATION forming part of Letters Patent No. 772,417, dated October 18, 1904.

Application filed September 12, 1903. Serial No. 173,007. (No model.)

To all whom it may concern:

Be it known that I, GIDEON P. KIDD, a citizen of the United States, residing at Roann, in the county of Wabash and State of Indiana, 5 have invented a new and useful Automatic Gravity-Gate, of which the following is a specification.

The invention relates to improvements in gates.

10 The object of the present invention is to improve the construction of gates and to provide a simple, inexpensive, and efficient one of great strength and durability, capable of being operated by the wheels of a vehicle and 15 of opening automatically by gravity after such operation and of similarly closing.

A further object of the invention is to provide a slidable gate of this character, which at the end of its opening and closing movement will be automatically cushioned or retarded to prevent it from being injured.

Another object of the invention is to provide an automatically-slidable gate which will be locked in both its open and closed positions and which will be supported and positively held against lateral movement to prevent animals from pushing through it.

With these and other objects in view the invention consists in the construction and novel 30 combination and arrangement of parts hereinafter fully described, illustrated in the accompanying drawings, and pointed out in the claims hereto appended, it being understood that various changes in the form, proportion, 35 size, and minor details of construction within the scope of the claims may be resorted to without departing from the spirit or sacrificing any of the advantages of the invention.

In the drawings, Figure 1 is a perspective view of an automatic gravity-gate constructed 40 in accordance with this invention and shown closed. Fig. 2 is a detail view, partly in section, illustrating the construction of one of the latches. Fig. 3 is a detail sectional view illustrating the construction of the oscillatory track from which the slidable gate 45 is suspended.

Like numerals of reference designate corresponding parts in all the figures of the drawings.

1 designates a sliding gate provided with upwardly-extending arms 2, forming continuations of the end bars of the gate and connected at their upper ends by a top bar 3, as shown; but a gate of any other desired construction may be employed. The gate is provided at the upper ends of the arms 2 with eyes or openings 4 for the reception of pivot portions 5 of hangers 6. The hangers 6, which are located at the ends of the gate, suspend the same from an oscillatory track 7 and are provided with grooved rollers or wheels 8, arranged to run on the track, as clearly shown in Fig. 3 of the drawings. The hangers are provided with depending shanks 65 or stems, and the pivots 5 extend horizontally from the lower ends of the shanks or stems, the latter being preferably bent at the pivots, and the outer terminals of the latter being provided with suitable means for retaining 70 the gate on them. By this construction the hangers are pivotally connected with the gate and are adapted to slide freely on the oscillatory track, which presents inclined portions to the hangers, as hereinafter explained. 75

The track 7, which is constructed of metal, is mounted on an oscillatory beam 8^a, which is enlarged at the center and pierced by a pivot 9, whereby it is pivotally mounted upon a central support 10. The central support 10, 80 which may be constructed in any desired manner, preferably consists of a pair of uprights or posts spaced apart to receive the oscillatory track and to provide a passage for the gate. The upper portions of the posts or uprights of the support 10 are pierced by the pivot 9; but any other suitable means may be employed for pivotally mounting the oscillatory track. The upper ends of the posts or uprights of the support 10 are connected by a 85 top piece 11, which is secured to a top bar 12, extending longitudinally of the oscillatory track and located above the same and connecting the central support with end posts or uprights 13 and 14.

The track 7, which may be secured to the oscillatory beam in any desired manner, is approximately T-shaped, as shown in Fig. 3, and it consists of an intermediate or central portion and end portions 15, which are 90 95 100

ranged at an angle to the central portion and which incline upward and outward from the same. The ends of the beam 8^a extend through vertical slots or openings of the posts or uprights 13 and 14, and the oscillation of the track is limited by stops 17, located at the lower portions of the slots or openings and preferably consisting of fastening devices which pierce the uprights or posts 17 and 10 which span the slots or openings, as clearly shown in Fig. 1 of the drawings.

The gate is adapted to slide by gravity from one end of the track to the other, and the track is oscillated by the means hereinafter described to elevate the gate-supporting portion or arm thereof to provide a steep incline for causing the gate to open quickly, and the incline at the other arm of the beam is adapted to retard the gate as the same completes 15 its movement, whereby the gate is prevented from coming violently in contact with the end uprights or posts 13 and 14. The hangers are arranged at the ends of the gate and are spaced apart, the distance between the hangers being greater than the length of either of the inclined end portions 15, so that the rollers of the hangers are adapted to run simultaneously on the straight intermediate portion and one of the inclined end portions 15. 20 The straight intermediate portion is arranged at a slight downward inclination when the track is tilted. While one of the rollers is riding up the inclined end portion at the latter part of the movement of the gate the other 25 roller is moving down the incline formed by the intermediate portion. The movement of the gate is checked in this manner, and at the same time the gate is prevented from rolling backward. The ends of the track are beveled or cut away at 18 to provide upper seats, which receive the adjacent roller or wheel of the gate when the same is at the limit of its movement in either direction. The beveled portion or seat 18 at the lower end of the 30 track is disposed at a slight inclination and is practically horizontal.

The gate is guided at the bottom by horizontally-disposed rollers or wheels 19, arranged in pairs and extending from opposite 35 sides of the posts or uprights of the central support 10. These horizontal guide-wheels 19 are mounted on upright portions of brackets 20, which are suitably secured to the support 10. The bottom of the gate is guided by the horizontal rollers or wheels and is prevented from binding at the central support.

The oscillatory track is operated or actuated by crank-shafts 21, located at opposite sides of the gate, a suitable distance therefrom, to 40 enable them to be operated by the wheels of a vehicle without liability of the draft-animals or the vehicle to be struck by the gate. Each crank-shaft is provided with a pair of crank-bends 22, arranged at right angles to 45 each other and adapted to be engaged by the

wheels of a vehicle and capable also of limiting the movement of the crank-shaft. The crank-shafts are also provided with upwardly-extending arms 23, which are connected by bars 24 and 25 with arms of an approximately 50 Y-shaped lever 26. The Y-shaped lever 26 is fulcrumed between its ends on the post or upright 13, and the inner ends of the bars 24 and 25 are connected with two of the arms of the Y-shaped lever at diametrically opposite points and are arranged above and below the pivot or fulcrum 27 of the Y-shaped lever. The arms of the Y-shaped lever connected to the inner ends of the bars 24 and 25 are straight and alined with each other. The 55 other arm, 28, of the approximately Y-shaped lever extends from the pivotal point and diverges from the upwardly-extending arm to which the bar 25 is connected. This upwardly-extending arm 29 oscillates from one 60 side of the pivotal point to the other, and when the gate is closed one of the crank-bends of each crank-shaft extends upward and is adapted to be swung inward and downward by the wheels of a vehicle, whereby the front 65 arm or portion of the oscillatory beam will be elevated for opening the gate. After a vehicle has passed through the gateway the crank-shafts are swung in the opposite direction to oscillate the beam and elevate the inner or 70 rear arm for closing the gate. Motion is communicated from the arm 28 of the approximately Y-shaped lever by means of a bar 30. The upper end of the bar is pivoted to the adjacent end of the oscillatory beam by a pin 31 75 or other suitable fastening device, and its lower end is connected with the arm 28 by a pivot 32. Each of the uprights or posts 13 and 14 is provided at the bottom with a keeper 33, consisting of an approximately U-shaped 80 piece having approximately parallel arms adapted to support the bottom of the gate against lateral movement to prevent any lateral pressure from opening the gate. The transverse connecting portion of the U-shaped 85 piece is pierced by suitable fastening devices 90 for securing the keeper to the upright or post to which it is applied.

The gate is locked in its open and closed 95 positions by resilient latches 34, secured to the gate at the ends thereof and projecting from each end of the same. Each of the end uprights or posts is provided with a slot or opening 35 and has a horizontal stop or piece 36 100 extending across the slot or opening and arranged to be engaged by the latch 34. The outer end of the latch 34 is angularly bent to provide a shoulder and to form an inclined outer portion 37, which enables the latch to readily ride over the stop 36. When the beam 105 is oscillated for actuating the gate, the latter is lifted, and this movement is sufficient to carry the latch out of engagement with the stop. The latch is guided into engagement 110 with the stop of the end post or upright by 115

the keeper, which preferably has its sides or arms slightly diverged for this purpose. The sides or arms of the keeper converge inwardly, and they are adapted to effectively hold the gate against lateral movement when the same is opened or closed.

Having thus fully described my invention, what I claim as new, and desire to secure by Letters Patent, is—

10 1. The combination of a support, an oscillatory beam pivotally mounted between its ends on the support, a track substantially T-shaped in cross-section carried by the beam and consisting of a central flange extending 15 from the beam and vertical flanges projecting upward and downward from the central flange, a sliding gate, hangers suspended from the track and provided with depending shanks having pivots extending beneath the track, 20 said pivots being also provided with upturned terminals, keepers located at the ends of the support and arranged to receive the bottom of the gate when the same is opened and closed,

and centrally-arranged guiding devices located at opposite sides of the gate at the bottom thereof, substantially as described.

2. The combination with an oscillatory track, of a slidable gate suspended therefrom and provided with latches, uprights having slots to receive the latches and provided with means for engaging the same, combined guides and keepers mounted on the uprights below the slots and having inwardly-converging side faces, said keepers being adapted to guide the latches into the slots and to prevent lateral movement of the gate, and antifriction-wheels arranged in pairs and located at opposite sides of the gate, substantially as described.

In testimony that I claim the foregoing as my own I have hereto affixed my signature in the presence of two witnesses.

GIDEON P. KIDD.
